UNITED STATES PATENT OFFICE.

WESCOTT BAILEY AND CHARLES E. DAKIN, OF PHILADELPHIA, PENNSYLVANIA, ASSIGNORS TO THE SONS OF VETERANS OF PENNSYLVANIA.

DESIGN FOR A BADGE.

SPECIFICATION forming part of Design No. 13,003, dated June 27, 1882.

Application filed May 8, 1882. Term of patent 7 years.

To all whom it may concern:

Be it known that we, WESCOTT BAILEY, a citizen of the United States, and CHARLES E. DAKIN, a subject of Great Britain, both residents of the city and county of Philadelphia, State of Pennsylvania, have invented and produced a new and original Design for a Badge for the members of a corporate body, called "The Sons of Veterans of Pennsylvania," of which the following is a specification, reference being had to the accompanying drawings.

Figures 1 and 2 are side elevations of the badge, taken from opposite sides.

On the face of the badge is a medallion with the monogram of the letters "S. V.," and the inscription "Gratia Dei Servatus, MDCCCLXXXI," said inscription being between two concentric circles of the medallion, the inner circle inclosing the monogram and also rays radiating from the center behind the monogram. Surrounding the medallion is a wreath of laurel and the ends of two cannons, which apparently cross at the back of the wreath and medallion, and the top of the medal is surmounted by an eagle.

The badge is suspended from a ribbon, which is attached to a fastening-pin consisting of a bar having a rim and bearing the inscription "Filii Veteranorum."

Upon the back of the badge is the representation of a belt with the ends buckled together, which incloses or surrounds the monogram "S. V. A."

We claim—

1. The design for a badge, consisting of the medallion with the inscription and monogram, the laurel wreath, the cannon, and eagle, as set forth.
2. The design for the pin of the badge, consisting of a bar having a rim and bearing the inscription "Filii Veteranorum," as set forth.
3. The design for the back of the badge, consisting of the representation of a belt surrounding the monogram "S. V. A.," as shown.
